UNITED STATES PATENT OFFICE.

SAMUEL BERGER, OF NEWARK, NEW JERSEY.

DESIGN FOR A COMBINED ICE-PICK AND SCOOP.

54,303.

Specification for Design.

Patented Dec. 23, 1919.

Application filed July 17, 1919. Serial No. 311,649. Term of patent 7 years.

To all whom it may concern:

Be it known that I, SAMUEL BERGER, a citizen of the United States, residing at Newark, in the county of Essex and State of New Jersey, have invented a new, original, and ornamental Design for a Combined Ice-Pick and Scoop, of which the following is a specification, reference being had to the accompanying drawing, forming part thereof.

The figures of the said drawing clearly show my new, original and ornamental de-

sign; and in the drawings, Figure 1 is a face view; Fig. 2 a side view; and Fig. 3 a rear view, showing my new, original and ornamental design.

I claim:—

The ornamental design for a combined ice pick and scoop as shown.

SAMUEL BERGER.
